ABSTRACT OF THE DISCLOSURE

Apparatus for crucible-free zone melting of a crystalline rod includes an induction heating coil for forming a melting zone in the rod. The coil surrounds and is spaced from the rod and is energizable to produce an inductive heating field around the rod. The coil and rod are relatively movable in the direction of the rod axis so as to pass the melting zone along the rod. The rod extends through an opening of a concentrator device which is located in the field between the heating coil and the melting zone and comprises a plurality of parts movable relative to each other within the field for varying the size of the opening so as to accommodate rods of respectively varying cross section therein. The concentrator device can be a subdivided ring with a silver surface, the subdivision of the ring being radially movable, or can comprise a pair of silvered metal strips aligned end to end and formed with a V-shaped notch at mutually adjacent ends thereof defining an aperture through which the rod extends.

My invention relates to apparatus for crucible-free zone melting of a rod-shaped member of crystalline material. Such apparatus is known in different embodiments. Usually, a crystalline rod that is to be processed is located in an evacuated vessel or in a vessel filled with protective gas. The rod consists, for example, of a semiconductor material such as germanium or silicon, or a metal, such as tungsten or molybdenum. The ends of the rod are gripped by holders and the rod is usually located in a vertical position. A heating device heats the rod along a narrow length thereof and thus forms a melting zone. This melting zone is passed along the length of the rod through relative movement of the heating device and the rod with respect to the longitudinal axis of the rod.

In heretofore known apparatus, an induction heating coil which surrounds and is spaced from the rod, serves as a heating device for the production of the melting zone. Thus, in the case of silicon, for example, the heating coil can be energized with a current having a frequency of 1-5 MHz. The semiconductor body can thus be melted by inductive heating produced by the coil. As a rule, the heating coil must surround the semiconductor rod relatively closely, in order to provide good coupling. This, of course, limits the growth diameter of the rod.

It is accordingly an object of my invention to provide a device for crucible-free zone melting which avoids the coupling difficulties encountered heretofore.

It is an additional object of my invention to provide apparatus for crucible-free zone melting which will make it possible to process crystalline rods of various cross sections and with various cross-sectional dimensions, without having to change the heating coil.

A further object of the invention is to provide a device which would aid also in producing crystalline rods whose cross-sectional dimensions vary along the rod length.

With the foregoing objects in view, I provide apparatus for crucible-free zone melting of a crystalline rod, par-

2

ticularly of semiconductor material, having two holders gripping the ends of the body and an induction coil surrounding and spaced from the rod for producing the melting zone in the rod, the induction coil being movable relative to the longitudinal axis of the rod. A concentrator device surrounding the rod is arranged in the field between the heating coil and the melting zone. The concentrator is divided into a plurality of parts adjustable with respect to each other so as to vary the area encompassed thereby.

Other features which are considered as characteristic for the invention are set forth in the appended claims.

Although the invention is illustrated and described herein as embodied in a device for crucible-free zone melting, it is nevertheless not intended to be limited to the details shown, since various modifications and structural changes may be made therein without departing from the spirit of the invention and within the scope and range of equivalents of the claims.

The construction and method of operation of the invention, however, together with additional objects and advantages thereof will be best understood from the following description of specific embodiments when read in connection with the accompanying drawings, in which:

FIG. 1 is an elevational view of an embodiment of my invention showing a concentrator and induction heating coil in position around the molten zone of a crystalline rod.

FIG. 2 is a top plan view of FIG. 1 with the induction heating coil removed.

FIGS. 3 and 4 are plan and elevational views, respectively, of an additional embodiment of a concentrator constructed in accordance with my invention.

Referring now to the drawings, and first, particularly, to FIG. 1, there is shown a melting zone 4 produced in a rod-shaped body 2, which may, for example, have a circular cross section. The melting zone 4 is produced by heating with an induction heating coil 3, which may be in the form of a flat, helically wound coil. The field of the heating coil 3 is concentrated by a concentrator device consisting of the parts 5a, 5b, 5c and 5d (FIG. 2). Concentrators per se are known from the inductive heating arts. They constitute divided or split rings of electrically conductive material which are located in the field of an induction coil. Due to the division of the concentrator, only such eddy currents are produced respectively within the individual parts as would ultimately concentrate the field in the area of the opening inside the concentrator. A closed ring, on the other hand, does not constitute a concentrator, because, with a closed ring, a field opposite to the field of the heating coil is produced, and the heating effect is completely nullified.

In the case at hand, where a concentrator is used for crucible-free zone melting, it can consist, preferably, of silver or of a copper component provided with a silver coating and connected preferably to a cooling loop, for example a water cooling system.

The German published patent application No. 1,094,710 discloses a method by means of which monocrystals are produced by seed crystals having a diameter considerably smaller than that of the semiconductor rod being processed. FIG. 1 shows such a crystal seed 6. With the device of my invention, no difficulties whatsoever are encountered in the processing of such a semiconductor rod since, by adjusting the concentrator, a type of concentration of the electromagnetic field may be obtained which makes the coupling of the heating coil 3 equally satisfactory in all positions. Thus, for example, the narrow crystal seed may have a diameter of approximately 3 to 5 mm., while the semiconductor rod 2 may have a diameter of 12 to 40 mm.

FIG. 2 indicates by the double-headed arrows the directions of motion of the parts 5a-5d of the concentrator 5,

which permit adjustment of the concentrator to the varying cross sections of the rod-shaped body to be processed. The device of my invention is also especially employable in cases where a desired change in the cross section of the rod, i.e. an enlargement or reduction, is to be effected by means of the crucible-free zone melting process.

FIGS. 1 and 2 illustrate a concentrator which has a circular ring-shaped cross section and which is subdivided into four parts. It is, of course, understood that the concentrator may also be divided into two or three or more than four parts. The shape of the opening in the concentrator may also conform to the cross-sectional shape of the rod being treated which can be square or rectangular, for example.

FIGS. 3 and 4 show another embodiment of a concentrator according to the invention, and consisting of two strips 11 and 12, aligned end to end and formed with V-shaped notches at the mutually adjacent ends. The strips 11, 12 are movable in the directions of the two-headed arrows.

If necessary, the concentrator can be made to lie completely inside the winding of the heating coil and be movable only from the outside of the heating coil. It is also possible to provide a concentrator above or below or both above and below the heating coil.

It is advisable to have all parts of the device of my invention enclosed by a relatively large vessel, which serves for maintaining the necessary vacuum, or the protective gas atmosphere, respectively as shown with related equipment, for example, in my Patent No. 2,972,525. The concentrator may also be placed in a relatively narrow vessel, for example a quartz tube, while the heating coil is located outside of the vessel, for example surrounding the quartz tube.

Relative motion between the heating coil and the treated rod may be effected by movement of the heating coil while the rod is tightly gripped inside the vessel, or by moving the rod while the heating coil is held fixed.

In the device of my invention, movement of the rod holder while the heating coil and the adjustment concentrator are fixedly mounted, appears to be more advantageous.

Movement of the parts 5a-5c (FIGS. 1 and 2) can be effected by suitably manipulating the holder rods 7 secured thereto.

Movement of the strips 11, 12 (FIGS. 3 and 4) can be effected by suitably manipulating the distant ends thereof.

I claim:

1. In apparatus for crucible-free zone melting of a crystalline rod, an induction heating coil for forming a melting zone in the rod, said coil surrounding and spaced from the rod and being energizable to produce an inductive heating field around the rod, said coil and rod being relatively movable in the direction of the rod axis so as to move the melting zone along the rod, and a concentrator device having an opening through which the rod extends, said concentrator device being located in the field between the heating coil and the melting zone and comprising a plurality of parts movable relative to each other within said field for varying the size of said opening so as to accommodate rods of respectively varying cross section therein.

2. In apparatus for crucible-free zone melting of a crys-

talline rod, an induction heating coil for forming a melting zone in the rod, said coil surrounding and spaced from the rod and being energizable to produce an inductive heating field around the rod, said coil and rod being relatively movable in the direction of the rod axis so as to move the melting zone along the rod, and a concentrator device having an opening through which the rod extends, said concentrator device being located below the heating coil in the field between the heating coil and the melting zone and comprising a plurality of parts movable relative to each other within said field for varying the size of said opening so as to accommodate rods of respectively varying cross section therein.

3. Apparatus according to claim 1 wherein said plurality of parts is greater than two.

4. In apparatus for crucible-free zone melting of a crystalline rod, an induction heating coil for forming a melting zone in the rod, said coil surrounding and spaced from the rod and being energizable to produce an inductive heating field around the rod, said coil and rod being relatively movable in the direction of the rod axis so as to move the melting zone along the rod, and a concentrator having an opening through which the rod extends, said concentrator being located in the field between the heating coil and the melting zone and comprising a subdivided

ring having a silver surface, the subdivisions of said ring being radially movable for varying the inner diameter of said ring whereby rods of varying cross-sectional area or shape can be accommodated by said concentrator.

5. In apparatus for crucible-free zone melting of a crystalline rod, an induction heating coil for forming a melting zone in the rod, said coil surrounding and spaced from the rod and being energizable to produce an inductive heating field around the rod, said coil and rod being relatively movable in the direction of the rod axis so as to move the melting zone along the rod, and a concentrator comprising a pair of metal strips aligned end to end each formed with a V-shaped notch at mutually adjacent ends thereof defining an aperture through which

the rod extends, said concentrator being located in the field between the heating coil and the melting zone, and the metal strips of said concentrator having a silver surface and being movable toward and away from each other for varying the size of said aperture whereby rods of

varying cross-sectional area or shape can be accommodated by said concentrator.

6. Apparatus according to claim 1 wherein said concentrator device is fixed with respect to said coil and relatively movable with respect to said rod in the direction of the rod axis.
